UNITED STATES PATENT OFFICE.

OTTO A. HOKANSON, OF WOODSTOCK, ILLINOIS, ASSIGNOR TO WOODSTOCK TYPEWRITER COMPANY, OF WOODSTOCK, ILLINOIS, A CORPORATION OF ILLINOIS.

ESCAPEMENT MECHANISM FOR TYPEWRITERS.

Application filed May 14, 1920. Serial No. 381,250.

To all whom it may concern:

Be it known that I, OTTO A. HOKANSON, a citizen of the United States, residing at Woodstock, in the county of McHenry and 5 State of Illinois, have invented certain new and useful Improvements in Escapement Mechanism for Typewriters, of which the following is a specification.

This invention relates to escapement 10 mechanism for controlling the movement of a typewriter platen carriage and has for its object the provision of mechanism of the class named which shall be of improved construction and operation.

15 The invention is exemplified in the combination and arrangement of parts shown in the accompanying drawing and described in the following specification, and it is more particularly pointed out in the appended 20 claims.

In the drawing—

Fig. 1 is a fragmentary vertical sectional view through a portion of a typewriter platen bed showing one embodiment of the 25 present invention applied thereto;

Fig. 2 is a horizontal section substantially on line 2—2 of Fig. 1;

Fig. 3 is a vertical section showing the escapement dog vibrator and escapement 30 wheel as viewed from the left in Fig. 2;

Fig. 4 is an elevation of the escapement dog vibrator viewed from the right in Fig. 2.

Fig. 5 is a fragmentary plan showing 35 a portion of the mechanism illustrated in Fig. 2 but having a slightly different adjustment; and

Fig. 6 is a fragmentary side elevation of 40 a portion of a typewriter having the present invention applied thereto.

In the embodiment of the invention shown in the drawing, a platen carriage bed 10 is provided with V-ways 11 along which ball bearings 12 are arranged to travel. A 45 platen carriage 13 is provided with V-ways 14 for engaging the ball bearings 12 by means of which the platen carriage is supported in position to move freely along the platen bed 10. A ball spacer 15 may be provided to retain the balls 12 in proper relative 50 position to one another, and the carriage is made in two sections adjustably connected to one another by cap screws to facilitate assembling and to permit adjustment of the 55 ways relative to one another to regulate the

bearing on the balls 12. The carriage 13 is provided with the usual spring motor for moving it in one direction along its supporting bed and has a rack bar 16 connected thereto to move in unison therewith. The teeth of the bar 16 engage the teeth of a pinion 17 which is carried by a shaft 18 journaled in a bearing member 19 inserted in an opening in the carriage bed 10 and held in place by having a portion thereof riveted into the 60 opening in the bed 10, as illustrated at 20, the opening in the bed being counterbored to hold the bearing 19 in place after it has been riveted. The shaft 18 projects below the bed plate 10 and has an escapement 65 wheel 21 secured thereto by any suitable means, such as set screws 22. The rotation of the escapement wheel 21 is controlled by a fixed dog 23 and a movable dog 24 which are carried by a rocker plate 25. The fixed 70 dog 23 is integral with or rigidly secured to the plate 25, and the movable dog 24 comprises a sliding bar 26 having a slot 27 engaging a pin 28 on the rocker plate 25. The plate 25 is provided with a tongue 29 which is 75 bent about the sliding bar 26 to hold it in position on the plate. A spring 30 is secured to a tail-piece 31 on the bar 26 and has its opposite end attached to a pin 32 on the plate 25 so that the spring normally urges 80 the dog 23 into position to meet one of the teeth 32 of the escapement wheel 21.

The rocker plate 25 is provided with bearing lugs 33 which are pivotally supported by stud screws 34 threaded in ears 35 which extend downwardly from a supporting plate 36. Lock nuts 37 are provided for holding the stud screws 34 in position. The plate 36 is carried by the lower face of the carriage bed 10 and a spring 38 is interposed between the tail-piece 39 of the plate 25 and the lower face of the plate 36, the spring 38 being held in place by a suitable recess and projection on the plates 36 and 25, respectively. The amplitude of the vibrations of the plate 25 upon its pivot supports 34 is controlled by adjustable screws 40 and 41 threaded through the plate 25 and provided with lock nuts 42 and 43, respectively. The ends of the screws 40 and 41 are arranged to 95 strike the lower face of the plate 36 to limit the movement of the rocker plate 25.

The rocker plate 25 is oscillated by a universal lever 44 pivoted on a shaft 45 supported by ears 46 extending downwardly 100

105

110

from the bracket member 47 which is secured to the carriage bed 10 by screws 48. The lower arm 49 of the lever 44 is provided with a tongue 50 cut in the plate which forms the arm 49 and offset therefrom to receive a finger 51 projecting from the end of the rocker plate 25. The upper arm 52 of the lever 44 is provided with a head 53 positioned in the path of movement of the type bars 54 as they swing into position to strike the platen 55. The bracket 47 extends upwardly to form type bar guides 56, and the arm 52 of the lever 44 extends through the opening between the guides 56 so that the type bars 54 will strike the head 53 and move the arm 52 into the broken line position shown in Fig. 1 just as the type is brought into contact with the platen.

The movement of the arm 52 from full to broken line positions, as shown in Fig. 1, will swing the dogs 23 and 24 carried by the rocker plate 25 downwardly so that the movable dog 24 will be shifted out of contact with the tooth 32 of the escapement wheel 21, and the fixed dog 23 will simultaneously engage the front face of the tooth previously contacting the face of the movable dog. As soon as the movable dog 24 is released from the escapement tooth 32 the dog will be drawn forwardly by the spring 30 until the rear end of the slot 27 engages the pin 28. As soon as the type bar 54 begins its return movement the lever arm 52 will be released and the rocker plate 25 will be swung about its pivotal supports by the spring 38 to return the dogs 23 and 24 to their uppermost position. This will free the tooth 32 of the escapement wheel 21 from the fixed dog 23 and permit a partial rotation of the escapement wheel for the reason that the dog 24 has been moved forwardly past the tooth of the escapement wheel and is no longer in position to re-engage the tooth of the escapement wheel previously in contact therewith. As the escapement wheel is rotated by a movement of the carriage platen the next succeeding tooth 32 will engage the face of the movable dog 24 and carry it back against the tension of the spring 30 until it is stopped by the contact between the pin 28 and the forward end of the slot 27. Thus, the carriage is fed the required amount at each stroke of a type bar and immediately after the type has been moved away from the platen.

As shown in Fig. 4, the active portions of the dogs 23 and 24 have their adjacent faces cut away leaving the portions of the dogs which contact with the teeth of the ratchet wheel spaced apart. The width of the space between the dogs is less than the thickness of the escapement wheel tooth so that when the dogs are shifted the face of one dog will be brought into alignment with the escapement tooth before the other dog has moved

out of contact with the tooth, but because the dogs are spaced apart the amount of movement to shift from one dog to the other is less than would be necessary if the dogs were in direct contact.

If it is desired to operate the escapement wheel in two steps instead of one, the active dog 24 may be held in advance of the fixed dog 23 by the slot 27 and the pin 28, as shown in Fig. 5. With this arrangement it is apparent that when the active dog 24 is moved out of engagement with the tooth 32 by the forward stroke of the type bar the escapement wheel will rotate until the tooth 32 strikes the fixed dog 23. Upon the return movement of the dog rocker the escapement wheel will make the second step in its movement to complete the feeding movement of the platen. By this arrangement the movement of the platen is divided into two steps, one of which occurs just before the type strikes the platen, and the other of which occurs after the type has left the platen on its return movement.

It should be noted that the universal member 44 for operating the dog rocker is connected directly with the rocker, and also is directly engaged by the type bar at a point adjacent the platen. By this arrangement there is very little chance for lost motion between the type bar and the dog rocker so that movement of the escapement mechanism can be very accurately timed with relation to the time of contact between the type and the platen, and since it is not necessary to allow for lost motion the amount of movement of the dog rocker can be reduced to a minimum. The direct connection of the universal member with the type bar and the dog rocker also permits of the use of very few parts and simple construction and facilitates compactness of arrangement. It should also be noted that the universal member is operated by contact with the outer portion of the type bar at the end of its positive stroke. This relieves the keys of the necessity of moving the escapement mechanism until the type bar has gained its maximum momentum so that the operation of the escapement mechanism is produced chiefly by the momentum of the type bar at the time that the momentum is the greatest. It should be noted also that the point of attachment between the universal member and the dog rocker is at a point away from the pivotal axis of the rocker beyond the escapement dogs. By this arrangement a leverage is obtained in the dog rocker itself for moving the dogs, thus reducing the force required for this purpose.

As will be seen from the drawing the construction is such that the parts may be compactly arranged in a minimum space and yet the parts are all of the simplest con-

struction so that practically all of the parts may be stamped from sheet metal. The carriage bed and the platen carriage have their body portions formed of a single web or plate arranged parallel with one another and spaced slightly apart by their cooperating ways forming a flat rectangular structure within the interior of which is arranged the rack and pinion mechanism for controlling the movement of the carriage on its bed. The arrangement of the shaft 18 extending through the bed plate not only brings the pinion 17 within the space between the carriage and its bed, but also makes it possible to arrange the escapement wheel 21 in a plane parallel with the bed plate so that the escapement wheel itself projects only a slight distance from the lower face of the bed plate, thus economizing space and making it possible to position the rocker plate 25 also directly beneath the bed plate and parallel therewith. Thus the entire escapement mechanism, together with the platen carriage and its bed plate, constitutes substantially a number of flat plates arranged one upon the other and spaced only short distances apart, thus providing a maximum economy of space and also employing parts of the simplest construction. In this connection it is noted also that the fixed dog 23 is formed by a part of the rocker plate 25 itself so that only one piece is necessary for these two elements of the mechanism.

Not only are the parts simply constructed and compactly arranged, but the entire escapement mechanism, as well as the universal member for operating the mechanism are all mounted upon the same support so that the escapement mechanism and the operating member therefor constitute a single unit, the parts of which have a definite fixed relation to one another independent of the other parts of the typewriter. Such an arrangement is especially advantageous when combined with a folding support for the carriage bed, such as is illustrated in Fig. 6 of the drawing, in which the bed plate 10 is shown carried by arms 60 pivotally mounted at 61 on the main base frame 62. Since the universal member 52 is supported by the bracket 47 on the carriage bed plate and is operated directly by the type bars without any connection with the key levers it is possible to fold the carriage with the entire escapement mechanism thereon, without the necessity of providing any separable driving connection to be made and broken when the carriage frame is swung into and out of operating position.

I claim:

1. In a typewriter, a platen carriage comprising a plate, a bed for said carriage comprising a plate arranged substantially parallel with the plate of said carriage, said

plates having cooperating ways for guiding said carriage on said bed and for spacing said plates from one another, an escapement wheel having a fixed plane of rotation arranged substantially parallel with said plates, and rack and pinion mechanism positioned within the space included between said plates and controlled by said escapement wheel for regulating the movement of said carriage on said bed. 75

2. In a typewriter, a platen carriage bed plate, a separately formed journal bearing extending transversely of said bed plate and secured thereto, a shaft journaled in said bearing, an escapement wheel secured to said shaft on one side of said bed plate and having the plane thereof extending in the direction of the plane of said bed plate, a pinion carried by said shaft on the side of said bed plate opposite said escapement wheel, a platen carriage arranged to travel on said bed plate, and a rack secured to said carriage and meshing with said pinion. 80

3. In a typewriter, a platen carriage bed, a platen carriage movable along said bed, and escapement mechanism for controlling the movement of said carriage on said bed, said escapement mechanism comprising a dog rocker positioned closely adjacent one face of said carriage bed and extending in the direction of the plane thereof. 85

4. In a typewriter, a platen carriage bed, a platen carriage movable on said bed, escapement mechanism for controlling the movement of said carriage on said bed, said mechanism comprising an escapement wheel arranged closely adjacent one face of said bed and having the plane thereof arranged to extend in the direction of the plane of said bed, and a dog rocker for controlling said escapement wheel, said dog rocker being positioned closely adjacent said face and arranged to extend in the direction of the plane of said face. 100

5. In a typewriter, a platen carriage comprising a main sheet metal body portion, a platen carriage bed comprising a main sheet metal body portion, an escapement wheel for controlling the movement of said carriage on said bed, and a rocker plate for controlling said escapement wheel, the body portions of said carriage and bed, the plane of said escapement wheel and said rocker plate all being arranged to extend in substantially parallel planes. 110

6. In a typewriter, a platen carriage bed, an escapement wheel mounted on said bed adjacent one face thereof, and a rocker plate for controlling the movement of said escapement wheel, said plate being pivoted adjacent said face of said bed to swing about a pivotal axis extending in the direction of the plane of said face. 125

7. In a typewriter, a platen carriage, a bed for said carriage, and escapement mech- 130

anism for controlling the movement of said carriage on said bed, said escapement mechanism comprising a pair of dogs and a rocker for controlling said dogs, said rocker being 5 pivoted on said bed to oscillate about an axis arranged closely adjacent one face of said bed and extending parallel with said face.

8. Escapement mechanism for a typewriter comprising a bed plate, a platen carriage 10 movable along said bed plate, a bracket secured to one face of said bed plate, a rocker pivoted to said bracket to oscillate about an axis extending parallel with said face, and means to limit the movement of said oscillating member to maintain said member in a position approximately parallel with said face.

9. Escapement mechanism for a typewriter comprising a platen carriage bed plate, an 20 escapement wheel arranged adjacent one face of said bed plate and having the plane thereof extending in a direction parallel to the plane of said face, dogs for controlling said escapement wheel, a rocker plate for 25 controlling said dogs, said rocker plate being arranged adjacent said face of said bed plate and pivoted to swing upon an axis extending in the direction of the plane of said face, and means for limiting the movement 30 of said rocker plate to maintain said plate in a position approximately parallel with the plane of said face.

10. The combination with a platen for a typewriter, of a carriage therefor, a bed for 35 said carriage, escapement mechanism for controlling the movement of said carriage on said bed, and a universal member for operating said escapement mechanism, said member having an arm extending adjacent said 40 platen and in the path of a type bar.

11. In a typewriter, a platen, a carriage therefor, a carriage bed on which said carriage is mounted to move, escapement mechanism mounted on said bed, a bracket secured to said bed and having type bar guides 45 carried thereby, and a lever mounted on said bracket and having one arm thereof connected with said escapement mechanism for operating said mechanism and having another arm thereof extending into a position 50 adjacent said platen and in the path of movement of a type bar.

12. An escapement mechanism for typewriters comprising a pivotally mounted dog 55 operating member, means engaging said member for actuating the same, and an escapement dog carried by said member at a point nearer the pivotal axis thereof than the point of engagement between said member and the actuating means therefor, but on the same side of said axis.

13. In a typewriter having a platen carriage frame movable away from operative 60 position, the combination of escapement mechanism mounted on said carriage frame,

and a universal member for operating said escapement mechanism mounted on said carriage frame and movable therewith.

14. A typewriter having a platen carriage frame, means for supporting said frame to permit movement thereof into and out of operating position, escapement mechanism mounted on said frame and movable therewith, and a universal member also mounted on said frame for operating said escapement mechanism and having means for engagement with the type bars of said typewriter to be actuated thereby.

15. A typewriter having a platen carriage frame supported for movement into and out of operating position, escapement mechanism carried by said frame and movable therewith, and a universal member connected with said escapement mechanism and supported by said frame for movement therewith, said universal member having a portion thereof disposed in the path of movement of the type bars of said typewriter when said platen carriage frame is in operating position so that said type bars will engage said portion and actuate said escapement mechanism when the typewriter is operated.

16. A typewriter having a platen carriage frame mounted thereon for movement into and out of operating position, a platen carriage movably mounted on said frame, escapement mechanism for operating said carriage, and a universal member for actuating said escapement mechanism, said universal member being connected with said escapement mechanism for all positions of said platen carriage frame.

17. A typewriter having a platen carriage frame mounted thereon and movable into and out of operating position, a platen carriage on said frame, escapement mechanism for operating said platen carriage, and a universal member mounted on said frame and connected with said escapement mechanism for all positions of said frame and positioned in the path of movement of the type bars of said typewriter when said frame is in operating position so that said universal member will be engaged by said type bars for actuating said escapement mechanism.

18. A typewriter having a platen frame arranged thereon for movement into and out of operating position, a platen carriage on said frame, and mechanism for operating said carriage mounted on said frame and movable therewith into and out of operating position, said mechanism being actuated by engagement with the type bars of said typewriter.

19. In a typewriter, a platen carriage frame having guideways thereon, a platen carriage comprising a plate movable on said frame and having flanges forming ways

at the edges thereof arranged to cooperate with the guideways on said frame, and means for adjusting one of said flanges to adjust the cooperating ways of said frame and carriage relative to one another.

20. In combination, a platen carriage frame having guideway thereon, and a platen carriage comprising sections adjustably connected to one another, each section being provided with a guideway arranged to cooperate with one of the ways on said frame and adjustable with said section to permit assembling of said carriage on said frame and the adjustment of said ways relative to one another.

21. A platen carriage frame having guides thereon provided with ways on the outer faces thereof, a platen carriage having guides thereon arranged to stride the guides on said frame and having ways arranged to cooperate with the ways on said frame, the guides on said carriage being adjustable toward and from one another to facilitate of assembling of said carriage on said frame and to permit adjustment of 25 said guideways relative to one another.

In testimony whereof I have signed my name to this specification on this 10th day of May, A. D. 1920.

OTTO A. HOKANSON.
